UNITED STATES PATENT OFFICE

EDWARD W. WILSON, OF NASHUA, NEW HAMPSHIRE, ASSIGNOR TO NASHUA SURE-HOLD COMPANY, OF NASHUA, NEW HAMPSHIRE, A CORPORATION OF MASSACHUSETTS

COLLAR SHAPE PRESERVER

Application filed February 2, 1931. Serial No. 512,906.

This invention relates to devices employed by laundries as temporary attachments for garments when the latter are being prepared for, and are being returned to customers; 5 and the invention is particularly designed for use in connection with shirts.

The portions of men's shirts which surround the necks of the wearers are referred to as neck bands. When the shirts have no 10 complete collars and are designed to have collars attached thereto by the users, the neck bands are comparatively narrow; that is, they are low in height. When the shirts are made with attached collars, the inner 15 neck band portions are usually higher and to their upper edges there are connected, integrally or by seams, the portions of the fabric which present the outer visible portions of the collars. Shirts of the former type are 20 referred to herein as neck-band shirts, and those of the latter type are referred to herein as collar-attached shirts.

The object of my invention is to provide 25 simple, easily applied attachments of low cost, which can be quickly applied to positions relatively to the collars or neck bands of either of the above-described types of shirts and which will reliably remain in positions to hold the front portions of the collars or neck bands in smooth conditions.

With said object in view, the invention 30 consists in the shaper or form substantially as hereinafter described and claimed.

Of the accompanying drawings:—

35 Figure 1 is a front view of a folded laundered shirt with one of my improved forms in position to support the front portions of the attached collar.

Figure 2 is a side view of the same, partly 40 broken out, and most of the attachment indicated by dotted lines to avoid confusion with the other lines.

Figure 3 represents a section on line 3—3 of Figure 2, on a larger scale.

45 Figure 4 represents a section on line 4—4 of Figure 1, on a larger scale.

Figures 5 and 6 are plan views of two of the kinds of shapers or forms which may be employed.

50 Similar reference characters indicate simi-

lar parts or features in all of the views.

A folded shirt *a* having an attached collar *b* and the usual upper button *f* in the neck band portion *c* of the shirt is conventionally illustrated in Figures 1 and 2. The neck band portion *c*, at its front has one end *d* provided with a button hole, and the other end *e* carries the button *f* all as usual. 55

Referring now to Figure 5, the form or shaper which is sometimes referred to as a formette, consists of a flat flexible strip 5, usually of cardboard or pasteboard, and so cut at its approximate mid-width or center as to provide a laterally elongated curved tongue 6. 60

The ends of the strip are cut on converging lines 7, 8, which meet to form points 9, the purpose of which will be presently explained. The upper edge 10 is curved to correspond with the curved shape which is assumed by the front fold line of the collar of the shirt when such collar is in a partially raised condition as illustrated by Figures 1 and 2. The lower edge of the strip is similarly curved, but preferably on a line which causes the strip to taper somewhat in width from its mid-width to its ends. 70

To apply the strip to position for use, it is converted to such shape, by slight bending, that it can be inserted inside the front of the neck band portion *c* of the shirt and slightly shifted endwise, or so manipulated, that its tongue 6 will enter between the ends *d*, *e*, of the said neck band (Fig. 3) and extend behind the lower portion of the button *f* (Fig. 4). This locks the attachment in the position indicated by dotted lines in Figures 1 and 2 from which position it can not be readily removed except by tearing. The fact that few, if any, of the attachments can be 80 removed from the shirts in condition to be used again is of little or no consequence as they are of very slight cost. 85

The pointed ends 9 of the strip aid in preventing it from being accidentally shifted endwise so as to unlock the tongue 6 from its position of interengagement as illustrated. 90

Instead of the ends of the strip having single points as illustrated in Figure 5, and 100

therefore presenting a simple tooth at each end, the ends may be serrated to provide a plurality of teeth at each end, as illustrated at 11 in Figure 6. And the tongue to be interlocked with portions of the shirt as described, instead of being curved and presenting a rounded end as illustrated in Figure 5, may be otherwise shaped. For instance the tongue may have a triangular form as illustrated at 12 in Figure 6.

If the device is to be used in connection with a shirt having a neck band and no complete collar, it is only necessary to insert a cheap stud, such as commonly used by laundries, in the usual two button holes of the shirt, and then apply the device to position in the same manner as hereinbefore described for collar-attached shirts. For such neck-band shirts, the attachments are usually narrower than illustrated in Figures 5 and 6.

While the device is especially designed for use by laundries in connection with shirts returned to their customers, it is also useful applied to shirts on exhibition for sale.

Having now described my invention, I claim:—

1. A form preserver comprising a flat flexible strip having a concave edge to fit inside the neck band portion of a shirt, said strip having a button-engaging tongue intermediate its width in position to cooperate with the upper button of the shirt.

2. A device of the character described, comprising a flexible strip having a curved edge and toothed ends and having a button-engaging tongue intermediate its width to cooperate with the upper button of a shirt.

3. A device of the character described, comprising a flexible strip having a curved upper edge and having an elongated tongue intermediate its width and length and extending longitudinally of the strip in position to extend between overlapped front ends of the neck band of a folded shirt.

4. A device of the character described, comprising a flexible strip having a curved upper edge and having an integral button-engaging curved tongue intermediate its width and length and extending longitudinally of the strip.

5. A device of the character described, comprising a flexible strip having a curved upper edge and an integral button-engaging triangular tongue intermediate its width and length and extending longitudinally of the strip.

In testimony whereof I have affixed my signature.

EDWARD W. WILSON.
